UNITED STATES PATENT OFFICE.

EDNEY B. CARTWRIGHT, OF CHATTANOOGA, TENNESSEE.

DESIGN FOR A FLOWER STAND.

Application filed July 9, 1926. Serial No. 18,289. Term of patent 14 years.

To all whom it may concern:

Be it known that I, EDNEY B. CARTWRIGHT, a citizen of the United States, residing at Chattanooga, in the county of Hamilton and State of Tennessee, have invented a new, original, and ornamental Design for a Flower Stand, of which the following is a specification, reference being had to the accompanying drawing, in which the figure is a perspective view of a flower stand, showing my new design.

I claim:—

The ornamental design for a flower stand, substantially as shown.

In testimony, that I claim the foregoing as my own, I have hereto affixed my signature.

EDNEY B. CARTWRIGHT.
